United States Patent Office

Des. 215,331
Patented Sept. 23, 1969

215,331

MEASURING CUP

James B. Swett, Barrington, R.I., and Sidney Z. Smith, Worcester, Mass., assignors to Rexall Drug and Chemical Company, Los Angeles, Calif., a corporation of Delaware

Filed Aug. 12, 1968, Ser. No. 13,094

Term of patent 14 years

Int. Cl. D7—99

U.S. Cl. D44—29

FIG. 1

FIG. 2

FIG. 4

FIG. 5

FIG. 3

FIGURE 1 is a perspective view of a measuring cup showing our new design;

FIGURE 2 is a bottom plan view;

FIGURE 3 is a cross section taken on line 3—3 of FIGURE 1;

FIGURE 4 is a cross section taken on line 4—4 of FIGURE 1; and,

FIGURE 5 is a cross section taken on line 5—5 of FIGURE 1.

We claim:

The ornamental design for a measuring cup, substantially as shown.
